METHOD AND MEANS FOR USE IN
MAKING SHOES

William Peter Le Rette, Lynn, Mass., assignor to
United Shoe Machinery Corporation, Paterson,
N. J., a corporation of New Jersey

Application February 1, 1935, Serial No. 4,545

37 Claims. (Cl. 12—14)

This invention relates to the manufacture of shoes, and more particularly to the treatment of the marginal portions of shoe uppers in lasted position with pressure and heat. The invention is herein illustrated by reference to operations on the foreparts of shoes, but it is to be understood that it is also applicable to operations on other portions.

In the manufacture of shoes of a type in which the marginal portion of the forepart of the upper, located between an insole and an outsole, lies, throughout its width in generally parallel relation to the bottom of the last on which the shoe is made, it is sometimes advantageous, especially if an adhesive is used to secure the upper in lasted relation to the insole, to subject the marginal portion of the upper in lasted position over the insole to pressure and heat. By this treatment any wrinkles in the margin of the upper, especially over the toe end of the insole, are effectively eliminated and a smooth seat close to the insole is provided to receive the outsole. If the upper is secured adhesively to the insole, moreover, such treatment is usually further beneficial because the heat accelerates the drying or hardening of adhesives such as are commonly used in lasting, thus affording increased insurance that the upper will be securely held in lasted position.

In view of the above and other considerations, the present invention provides an improved method including the application of pressure and heat to the marginal portion of an upper over an insole, and novel means for use in the practice of the method. In one aspect, an object of the invention is to insure against any possible displacement or loosening of the upper in the interval between the laying of its margin over the insole and the application of the pressure and heat, and to this end the invention provides for pressing upon the insole, and preferably also heating, a portion of the overlaid margin of the upper located at a distance from the extreme edge of the shoe bottom while the portion nearer the edge of the shoe bottom is still held under the overlaying pressure, and for then releasing from the overlaying pressure the portion nearer the edge and applying pressure and heat thereto while the pressure on the portion at a distance from the edge is maintained. By this procedure no opportunity is afforded for any displacement of the upper from its final lasted position before the pressure and heat are applied. In the illustrated application of the invention to the lasting of the toe ends of shoes in a bed-lasting machine

the pressure and heat are applied first to a portion of the upper extending inwardly over the insole beyond the edges of the toe-lasting wipers while the wipers are still over the shoe bottom in holding engagement with the upper, after which the wipers are retracted from over the shoe bottom and the portion uncovered by their retractive movement is subjected to pressure and heat. The novel means herein disclosed for thus treating the upper comprises a heated plate 10 formed to engage the upper inwardly of the edges of the wipers and thus to apply the pressure and heat in that location while also preventing any loosening or displacement of the upper from lasted position when the wipers are thereafter retracted, and another heated plate movable into engagement with the portion of the upper uncovered when the wipers are thus retracted. In the construction shown the last-mentioned plate is flexibly conformable to the 20 contour of the shoe bottom and is pressed upon the shoe bottom through a plurality of spring-controlled plungers. The two plates, as further herein illustrated, are parts of a pressing device which is mounted for movement into and out of 25 a position opposite the bottom of the shoe, but it is to be understood that in some aspects of the invention the pressing device is not necessarily an attached part of a lasting machine.

Further in accordance with the novel method, 30 in one of its aspects, heat of a higher degree is applied to the portion of the overlasted margin of the upper located at a distance from the edge of the shoe bottom than to the portion nearer the edge. This affords better insurance that the 35 portion where wrinkles due to the gathering of the margin around the toe, for example, are most prominent will be effectively smoothed out by the shrinking action of the heat combined with the pressure, without danger that any portion 40 which might be visible in the finished shoe will be damaged by the heat. To carry out this part of the method, the plate which engages the upper inwardly of the edges of the toe wipers in the 45 novel pressing device herein shown has an electrical heating unit mounted therein, by which unit also the plate which engages the upper nearer the edge of the shoe bottom is heated but to a lower degree than the other plate by reason of 50 its comparative remoteness from the source of heat and the manner in which it is constructed and mounted. The invention further provides for the application of relatively greater pressure to the inner more wrinkled portion of the mar- 55

gin of the upper where greater pressure is desirable than nearer the edge of the shoe bottom.

The novel method and novel features of the means herein disclosed for use in the practice of the method will now be more particularly described by reference to the accompanying drawings and pointed out in the claims.

In the drawings,

Fig. 1 is a perspective view of a portion of a bed-lasting machine having upper-pressing means constructed in accordance with the present invention for the practice of the novel method, the parts being shown in the positions which they occupy when the pressing means is first applied to the shoe in engagement with the portion of the upper which extends inwardly beyond the edges of the toe wipers;

Fig. 2 is a vertical section longitudinally of the shoe, showing the pressing device with the parts in the same positions as illustrated in Fig. 1;

Fig. 3 is a vertical section laterally of the shoe showing the lower portion of the pressing device with the parts in the same positions as shown in Figs. 1 and 2; and

Fig. 4 is a section similar to Fig. 3, but showing the parts in the positions which they occupy with the pressing device in engagement also with the portion of the upper uncovered by retractive movement of the toe wipers.

The bed-lasting machine herein shown as having upper-pressing means constructed in accordance with the present invention is one of a well-known type characteristic features of which, relating especially to the means for lasting the toe end of the shoe, are illustrated and described in detail, for example, in United States Letters Patent No. 1,284,870, granted on November 12, 1918 upon an application of Matthias Brock. Only a portion of the machine, therefore, is included in the drawings and only such parts as it is necessary to refer to for an understanding of the invention will be hereinafter mentioned. It is further to be understood that the invention is not limited to machines of the particular type illustrated or to use with such machines.

The shoe and its last are mounted as usual at the heel end on a jack (not shown), and at its forepart the shoe is supported on a toe rest 10 against downward pressure on its bottom face. The shoe thus supported is operated upon at the toe end by toe-embracing wipers 12 which, in machines of the illustrated type, are moved upwardly by a treadle to wipe the toe end of the upper heightwise of the last to the edge of the shoe bottom and are advanced and closed by a hand lever to wipe the marginal portion of the upper inwardly over the insole, the shoe herein shown being one of a type in which the marginal portion of the upper is thus wiped inwardly over the insole so as to lie throughout its width in substantially parallel relation to the bottom of the last. The machine shown further includes a toe band 14 (Fig. 1) for embracing and clamping the upper against the last near the edge of the shoe bottom in the manner disclosed in the above-mentioned Letters Patent, although such a toe band may be and often is omitted. For convenience it is not shown in Figs. 2, 3 and 4.

For purposes of the present invention the machine is provided with an upper-pressing device supported as hereinafter described for movement into and out of position over the bottom of the forepart of the shoe and having two upper-

pressing members or plates 16 and 18 (Figs. 2, 3 and 4). The plate 16 in the construction shown is a rigid plate curved similarly to the edge of the portion of the shoe bottom along which the plate extends and so formed as to engage and press upon the insole, as shown in Figs. 2 and 3, that portion of the upper which extends inwardly over the insole beyond the edges of the wipers 12 while the wipers are still over the shoe bottom in holding engagement with the upper. This plate is heated by an electrical heating unit 20 mounted therein, to which an electrical current is conducted through wires in a flexible cable 22 (Fig. 1). The plate 16 is pressed down upon the shoe bottom through a spring 24 by downward movement of a supporting plate 26 between which and the plate 16 the spring is mounted. A portion of the plate 16 extends outwardly beyond its central upper-engaging portion in spaced relation to the shoe bottom, and in openings formed in this outwardly extending portion of the plate are a plurality of spring-controlled plungers 28 arranged in a series along the edge of the shoe bottom. To the lower ends of these plungers is riveted the upper-pressing plate 18 to which heat is conducted from the heating unit 20 through the plate 16 and the plungers. The plungers 28 have stems 30 of smaller diameter which extend upwardly through holes in the supporting plate 26 and have mounted thereon springs 32 through which downward pressure is transmitted from the plate 26 to the plungers. The lower ends of the plunger 28 are diametrically enlarged for engagement with downwardly facing shoulders 34 on the plate 16, and the stems 30 at their upper ends are provided with cotter pins 36 arranged to engage washers 38 on the top of the plate 26. By this means accordingly relative separating movement of the plate 16 and the plate 26 under the influence of the spring 24 is limited, the parts being initially so positioned that the upper-pressing plate 18 is upraised a substantial distance above the upper-engaging face of the plate 16, so that the latter may be applied to the upper while the wipers are over the shoe bottom, as illustrated in Figs. 2 and 3. The plate 16 is pressed down upon the margin of the upper through the spring 24 as hereinabove described, and thereafter as the plate 26 is further depressed against the resistance of this spring the several plungers 28 are moved downwardly to apply the pressing plate 18 to a portion of the upper which is exposed by retractive movement of the wipers from over the shoe bottom while the plate 18 is holding the upper securely in lasted position.

The plate 18 consists of a comparatively thin strip of metal curved lengthwise similarly to the edge of the shoe bottom and lying close to the central upper-engaging portion of the plate 16. The plate 18 is preferably flexible and resilient, so that it conforms itself to the contour of the shoe bottom as it is pressed downwardly by the several plungers 28. It will be understood that at the end of the downward movement of the plate 26 the several springs 32 controlling the plungers 28 are substantially compressed. The plates 16 and 18 thus cooperate to apply pressure and heat substantially throughout the width of that portion of the upper which is lasted inwardly over the insole. In the construction herein shown these plates are arranged to act not only upon the margin of the toe portion of the upper lasted inwardly by the wipers 12, but also upon a portion of the upper extending substantially as 75

far rearwardly as the ball line of the shoe. The forepart of the upper at the rear of the toe portion may have been already lasted before the shoe is presented to the bed-lasting machine, or 5 may be lasted by hand while the shoe is in this machine preparatory to the use of the pressing device on the upper. While it will be evident that the steps performed at the rear of the toe portion are not precisely the same as at the toe portion, because the upper beyond the ends of 10 the toe wipers is not held under overlaying pressure when the plate 16 is applied thereto, nevertheless the heated plates 16 and 18 act in other respects with substantially the same beneficial effects at the rear of the toe as at the toe portion, especially if the forepart at the rear of the toe 15 is lasted with adhesive.

The plate 18 is heated to a lower degree than the plate 16, partly because it is comparatively 20 remote from the heating unit 20 and partly because the plungers 28, through which the heat is conducted, are spaced apart and are mounted somewhat loosely in the holes in the plate 16. The comparatively thin plate 18, moreover, tends 25 to dissipate the heat more rapidly than the plate 16. It is accordingly practicable to apply to the upper through the plate 16 heat of a considerably higher degree than could safely be applied at or near the edge of the shoe bottom because 30 of danger of damaging a portion of the upper which might be visible in the finished shoe; and this is desirable as affording better insurance that the inner portion of the overlasted margin of the upper, where wrinkles due to the gathering of 35 the margin around the toe are most prominent, will be effectively smoothed by the shrinking action of the heat. Provision is further afforded for the application of greater pressure to the inner more wrinkled portion of the margin of the upper than to the portion near the edge of the insole where excessive pressure might have the undesirable 40 effect of squeezing or spreading the upper in an outward direction. For this purpose the spring 24 through which the inner plate 16 is pressed down on the shoe bottom is considerably 45 stronger and is subjected to greater compression by the plate 26 than each of the springs 32 acting respectively on different portions of the flexible plate 18.

The plate 26 in its downward and upward movements relatively to the plate 16 is further guided by pins 49 and 42 which extend upwardly from the plate 16 into tubular projections 44 and 46 on the lower side of the plate 26. The plate 26 and other portions of the upper-pressing device are supported on one end of an arm or carrier 48 which is slidably movable lengthwise in a holder 50 supported on a vertical rod 52. The arm 48 has a ball-shaped forward end 54 which lies in a concave seat formed in the upper face of the plate 26, as shown in Fig. 2, and secured to this plate is a bracket 56 which extends over the top of the ball-shaped end 54 to support the pressing device on the arm 48. It will be evident that this construction permits the pressing device to be turned horizontally about the ball-shaped end 54 to assist in positioning the device in proper relation to the shoe bottom and also permits universal tipping movements of the device so that the plate 16 may adjust itself to the bottom of the shoe. Projecting from the plate 26 is a handle 58 to assist the operator in properly positioning the device, and secured to the arm 48 is a curved arm 60 which underlies the handle 58 and assists in preventing excessive tipping movements 75

of the pressing device when the latter is in its idle position. The holder 50 and the rod 52 are of substantially the same construction and are operated in the same way as means provided heretofore in machines of the illustrated type for supporting a holdown member and for pressing the member down upon the shoe bottom, as disclosed in Letters Patent No. 1,120,822, granted on December 15, 1914 upon an application of E. L. Keyes. As more fully illustrated and described 10 therein, the holder 50 is mounted to turn about the rod 52, and the rod is moved downwardly by means of a treadle connected thereto and is locked in its depressed position. Accordingly, in the construction herein shown, the provision for turning movement of the holder 50 about the rod 52 permits the operator to swing the upper-pressing device from an initial idle position at the rear of the machine to a position over the bottom of the forepart of the shoe, after which, by use of 20 the treadle, the operator moves the rod 52 and the holder 50 downwardly to apply the plate 16 first to the shoe and thereafter to apply the plate 18 to the shoe in the manner hereinbefore described. Further to assist in positioning the 25 pressing device in proper relation to the shoe before it is applied to the shoe the construction shown includes a lever 62 which is pivotally mounted on that portion of the arm 48 which is slidably movable in the holder 50, the lever having a pin-and-slot connection at 64 with the holder 50. By use of this lever the operator may slide the arm 48 forwardly or rearwardly in the holder 50 as desired.

The steps leading up to the use of the upper- 35 pressing device on the shoe will vary in accordance with the preferences of different manufacturers. Commonly, however, in lasting toes with an adhesive the several layers of upper materials, including the lining and the toe box, are first 40 wiped upwardly around the toe end of the last by the wipers 12 and the marginal portions of the several layers are then wiped preliminarily inward over the insole by the wipers. Thereafter the wipers are retracted from over the shoe bottom and by use of a hand knife the operator trims the margin of all the layers except the outer layer approximately as far back as the edge of the insole. He then applies a suitable adhesive to the margin of the outer layer or to the insole, 45 or to both, and wipes the upper materials again upwardly and wipes the margin of the outer layer inwardly over the insole into position to be secured by the adhesive. If the forepart of the shoe rearwardly of the toe portion has not already been lasted before the shoe comes to the machine, the operator will perform the lasting operation in that location by hand before or after lasting the toe portion, preferably using adhesive to secure the upper to the insole. While the toe 50 wipers are still over the shoe bottom in holding engagement with the upper over an area extending a substantial distance inwardly from the edge of the shoe bottom, the operator swings the upper-pressing device into position over the bottom 55 of the forepart of the shoe, adjusts it in proper relation to the shoe, and lowers it by the treadle connected to the rod 52 for that purpose to bring the inner heated pressing plate 16 into engagement with a portion of the overlasted margin of the upper which extends inwardly beyond the edges of the wipers, as illustrated in Figs. 1, 2 and 3. Thereafter, while the plate 16 is in pressing and holding engagement with the margin of the 75

upper, the operator retracts the wipers 12 from over the shoe bottom and by further depression of the treadle forces the plate 26 downwardly against the resistance of the spring 24 to apply 5 the outer flexible pressing plate 18 to the portion of the upper uncovered by the retractive movement of the wipers. The downward movement of the plate 26 is continued until the several springs 32 are substantially compressed in order to apply 10 sufficient pressure to the plate 18. It will be evident that through the comparatively heavy spring 24 the plate 16, which acts on the more wrinkled inner portion of the gathered margin around the toe, is forced against the upper with 15 greater pressure than is applied through the springs 32 to the plate 18, a relatively higher degree of heat also being applied to the upper by the plate 16 as hereinbefore explained. The pressing plates 16 and 18 are maintained in pressing engagement with the upper as long as desired, after which the pressing device is withdrawn from the shoe and returned to its idle position. The plates may, for example, be left in contact with the shoe while the operator lasts 20 the heel end of the shoe in the customary manner, if the heel end has not already been lasted.

Having described the invention, what I claim as new and desire to secure by Letters Patent of the United States is:

30 1. That improvement in methods of lasting shoes which consists in laying the marginal portion of an upper inwardly over an insole and maintaining overlaying pressure thereon from the edge of the shoe bottom inwardly over an area terminating short of the edge of the upper, then pressing the upper upon the insole in a location farther inwardly from the edge of the shoe bottom than said area while applying heat thereto, and while pressing the upper upon the insole in that location releasing the upper nearer the edge of the shoe bottom from the overlaying pressure and then applying pressure and heat to that portion of the upper.

45 2. That improvement in methods of lasting shoes which consists in laying the marginal portion of an upper inwardly over an insole with an adhesive between the upper and the insole and maintaining overlaying pressure on the upper from the edge of the shoe bottom inwardly over an area terminating short of the edge of the upper, then applying a heated presser to the upper in a location farther inwardly from the edge of the shoe bottom than said area, and while holding the upper pressed upon the insole by said heated presser releasing the upper nearer the edge of the shoe bottom from the overlaying pressure and applying another heated presser to that portion of the upper.

55 3. That improvement in methods of lasting shoes which consists in wiping the marginal portion of an end of an upper inwardly over an insole on a last so that said marginal portion lies throughout its width in generally parallel relation to the bottom of the last by the use of end-lasting wipers, pressing upon the insole a portion of the upper extending inwardly over the insole beyond the wipers while the wipers are still in position to hold the upper, and while maintaining the pressure on said inwardly extending portion 60 of the upper withdrawing the wipers from over the shoe bottom and applying pressure and heat to the portion of the upper exposed by the withdrawal of the wipers.

70 4. That improvement in methods of lasting shoes which consists in wiping the marginal por-

tion of an end of an upper inwardly over an insole on a last so that said marginal portion lies throughout its width in generally parallel relation to the bottom of the last by the use of end-lasting wipers, applying a heated presser to a portion of the upper extending inwardly over the insole beyond the wipers while the wipers are still in position to hold the upper, and while maintaining said heated presser in pressing engagement with the upper withdrawing the wipers from over the shoe bottom and applying an additional heated presser to the portion of the upper exposed by the withdrawal of the wipers.

5 5. That improvement in methods of making shoes which consists in laying the marginal portion of an upper inwardly over an insole, and thereafter applying pressure and heat to the overlaid marginal portion of the upper with a substantially higher degree of heat at a distance from the edge of the shoe bottom than nearer said edge.

15 6. That improvement in methods of making shoes which consists in laying the marginal portion of an upper inwardly over an insole with an adhesive between the upper and the insole, and thereafter pressing the overlaid marginal portion of the upper substantially throughout its width upon the insole and also applying heat thereto with a substantially higher degree of heat adjacent to the edge of the upper than adjacent to the edge of the shoe bottom.

25 7. That improvement in methods of lasting shoes which consists in wiping the marginal portion of an end of an upper inwardly over an insole on a last so that said marginal portion lies throughout its width in generally parallel relation to the bottom of the last by the use of end-lasting wipers, applying a heated presser to a portion of the upper extending inwardly over the insole beyond the wipers while the wipers are still in position to hold the upper, and while maintaining said heated presser in pressing engagement with the upper withdrawing the wipers from over the shoe bottom and applying an additional presser, heated to a lower degree than said first-named presser, to the portion of the upper exposed by the withdrawal of the wipers.

35 8. That improvement in methods of making shoes which consists in laying the marginal portion of an upper inwardly over an insole, and thereafter pressing the overlaid marginal portion of the upper upon the insole while applying thereto substantially greater pressure at a distance from the edge of the shoe bottom than nearer said edge.

45 9. That improvement in methods of making shoes which consists in laying the marginal portion of an upper inwardly over an insole, and thereafter pressing the overlaid marginal portion of the upper upon the insole and applying heat thereto with greater pressure and a higher degree of heat at a distance from the edge of the shoe bottom than nearer said edge.

55 10. That improvement in methods of lasting shoes which consists in wiping the marginal portion of an end of an upper inwardly over an insole on a last so that said marginal portion lies throughout its width in generally parallel relation to the bottom of the last by the use of end-lasting wipers, pressing upon the insole a portion of the upper extending inwardly over the insole beyond the wipers while the wipers are still in position to hold the upper and applying heat to the portion thus pressed, and while maintaining such pressure on the upper withdrawing

the wipers from over the shoe bottom and applying to the portion of the upper exposed by the withdrawal of the wipers pressure and heat both substantially less than applied to the portion of the upper extending farther inwardly.

5 11. In a lasting machine, the combination with means for laying the marginal portion of a shoe upper inwardly over an insole, of means for pressing the overlaid marginal portion of the upper upon the insole in a location where the upper is not engaged by the overlaying means while the upper is still under control of the overlaying means, and additional means for thereafter pressing upon the insole a portion of the upper exposed by retractive movement of the overlaying means.

10 12. In a lasting machine, the combination with means for laying the marginal portion of a shoe upper inwardly over an insole, of means arranged to press upon the insole a portion of the upper extending inwardly over the shoe bottom beyond the overlaying means while the upper is still under control of the overlaying means, and additional means arranged to press the upper upon the insole in a location nearer the edge of the shoe bottom than said first-named pressing means after retractive movement of the overlaying means.

15 13. In a lasting machine, the combination with means for laying the marginal portion of a shoe upper inwardly over an insole, of means for applying pressure and heat to the overlaid marginal portion of the upper, said last-named means having different portions relatively movable heightwise of the shoe and arranged respectively to press the upper upon the insole in a location at a distance from the edge of the shoe bottom while the upper is still under control of the overlaying means and to press the upper upon the insole in a location nearer the edge of the shoe bottom after the overlaying means has been withdrawn from upper-controlling position.

20 14. In a lasting machine, the combination with means for laying the marginal portion of a shoe upper inwardly over an insole, of means arranged to press upon the insole a portion of the upper extending inwardly over the shoe bottom beyond said overlaying means while the upper is still under control of the overlaying means, and additional means for pressing the upper upon the insole in a location nearer the edge of the shoe bottom than said first-named pressing means after retractive movement of the overlaying means from over the shoe bottom, said additional means being constructed to apply less pressure to the upper than said first-named pressing means.

25 15. In a lasting machine, the combination with means for laying the marginal portion of a shoe upper inwardly over an insole, of means for pressing upon the insole a portion of the upper extending inwardly over the shoe bottom beyond said overlaying means while the upper is still under control of the overlaying means and for applying heat to the portion of the upper thus pressed, and additional means constructed and arranged to press the upper upon the insole in a location nearer the edge of the shoe bottom than said first-named pressing means after retractive movement of the overlaying means and to apply to the upper in that location heat of a lower degree than that applied by said first-named pressing means.

30 16. In a lasting machine, the combination with wipers for wiping the marginal portion of

a shoe upper inwardly over an insole around an end of the shoe bottom, of means arranged to press upon the insole a portion of the upper extending inwardly over the shoe bottom beyond the wipers while the wipers are still in position to hold the upper, and additional means for thereafter pressing upon the insole a portion of the upper exposed by retractive movement of the wipers.

35 17. In a lasting machine, the combination with wipers for wiping the marginal portion of a shoe upper inwardly over an insole around an end of the shoe bottom, of means for applying pressure and heat to the marginal portion of the upper around the end of the shoe bottom, 15 said means having different portions arranged respectively to press upon the insole a portion of the upper extending inwardly over the shoe bottom beyond the wipers while the wipers are still in position to hold the upper and to press 20 upon the insole a portion of the upper located nearer the edge of the shoe bottom after the wipers have been withdrawn from over the shoe bottom.

40 18. In a lasting machine, the combination with wipers for wiping the marginal portion of a shoe upper inwardly over an insole around an end of the shoe bottom into position to be secured adhesively to the insole, of means for applying pressure and heat to the marginal portion of the upper around the end of the shoe bottom, said means comprising a heated member for first engaging and pressing upon the insole a portion of the upper extending inwardly over the shoe bottom beyond the wipers to hold the 35 upper when the wipers are thereafter retracted from upper-engaging position and comprising also another heated member movable heightwise of the shoe relatively to said first-named member for pressing upon the insole a portion of the 40 upper exposed by such retractive movement of the wipers.

45 19. In a lasting machine, the combination with wipers for wiping the marginal portion of a shoe upper inwardly over an insole around an end 45 of the shoe bottom, of a device for applying pressure and heat to the marginal portion of the upper around the end of the shoe bottom, said device comprising means for first engaging and pressing upon the insole a portion of the upper extending inwardly over the shoe bottom beyond the wipers while the wipers are still over the shoe bottom and additional means flexibly conformable to the contour of the shoe bottom and 50 movable thereafter into position to press upon the insole a portion of the upper exposed by retractive movement of the wipers from over the shoe bottom.

55 20. In a lasting machine, the combination with wipers for wiping the marginal portion of a shoe upper inwardly over an insole around an end of the shoe bottom, of a device for applying pressure and heat to the marginal portion of the upper around the end of the shoe bottom, 65 said device comprising a heated plate arranged to press upon the insole a portion of the upper extending inwardly over the shoe bottom beyond the wipers while the wipers are still over the shoe bottom and another heated plate flexibly conformable to the contour of the shoe bottom and movable relatively to said first-named plate into position to press upon the insole a portion of the upper exposed by retractive movement of the wipers from over the shoe bottom. 70 75

21. In a lasting machine, the combination with wipers for wiping the marginal portion of a shoe upper inwardly over an insole around an end of the shoe bottom, of a member for 5 pressing upon the insole a portion of the upper extending inwardly over the shoe bottom beyond the wipers while the wipers are still over the shoe bottom, another member for thereafter pressing upon the insole a portion of the upper exposed by retractive movement of the wipers from over the shoe bottom, and means for heating both said members but for heating said first-named member to a higher degree than the other member.
- 15 22. In a lasting machine, the combination with means for laying the marginal portion of a shoe upper inwardly over an insole, of a device for applying pressure and heat to the overlaid marginal portion of the upper, and a member 20 movable heightwise of the shoe to press said device upon the shoe bottom, said device having a portion arranged to engage and press the upper in a location at a distance from the edge of the shoe bottom in response to movement of said member and another portion arranged thereafter to engage and press the upper in a location nearer the edge of the shoe bottom in response to further movement of said member.
- 25 23. In a lasting machine, the combination with 30 wipers for wiping the marginal portion of a shoe upper inwardly over an insole around an end of the shoe bottom, of a device for applying pressure and heat to the marginal portion of the upper around the end of the shoe bottom, and a member 35 movable heightwise of the shoe to press said device upon the shoe bottom, said device having means arranged to engage and press a portion of the upper extending inwardly over the shoe bottom beyond the wipers in response to 40 movement of said member while the wipers are over the shoe bottom and additional means operative in response to further movement of said member to engage and press the upper in a location nearer the edge of the shoe bottom after re- 45 tractive movement of the wipers.
24. In a lasting machine, the combination with 50 wipers for wiping the marginal portion of a shoe upper inwardly over an insole around an end of the shoe bottom, of a device for applying pressure and heat to the marginal portion of the upper around the end of the shoe bottom, and a support for said device mounted for movement to 55 carry the device from an idle position to a position opposite the shoe bottom and for movement also heightwise of the shoe to press the device upon the upper, said device having means arranged to be carried first into engagement with a portion of the upper extending inwardly over the shoe bottom beyond the wipers while 60 the wipers are still over the shoe bottom and additional means movable thereafter into engagement with a portion of the upper exposed by retractive movement of the wipers from over the shoe bottom.
- 65 25. A device for pressing upon an insole the marginal portion of an upper wiped inwardly over the insole by end-lasting wipers, said device comprising means for first pressing upon the insole a portion of the upper extending inwardly over 70 the insole beyond the wipers while the wipers are still over the shoe bottom and additional means for thereafter pressing upon the insole a portion of the upper exposed by retractive movement of the wipers from over the shoe bottom.
- 75 26. A device for pressing upon an insole the marginal portion of an upper wiped inwardly over the insole by end-lasting wipers, said device comprising a heated member for first pressing upon the insole a portion of the upper extending 5 inwardly over the insole beyond the wipers while the wipers are still over the shoe bottom and another heated member movable heightwise of the shoe relatively to said first-named member for thereafter pressing upon the insole a portion 10 of the upper exposed by retractive movement of the wipers from over the shoe bottom.
27. A device for pressing upon an insole the marginal portion of an upper wiped inwardly over the insole by end-lasting wipers, said device comprising means for first pressing upon the insole a portion of the upper extending inwardly over the insole beyond the wipers while the wipers are still over the shoe bottom and also means movable thereafter heightwise of the shoe to press 20 upon the insole a portion of the upper exposed by retractive movement of the wipers from over the shoe bottom, said last-named means being conformable to the contour of the shoe bottom in response to the pressure of the shoe thereon.
28. A device for pressing upon an insole the marginal portion of an upper wiped inwardly over the insole by end-lasting wipers, said device comprising a plate formed to engage and press a portion of the upper extending inwardly over the 30 insole beyond the edges of the wipers while the wipers are still over the shoe bottom and another plate flexibly conformable to the contour of the shoe bottom and movable thereafter heightwise of the shoe relatively to said first-named plate 35 to press upon the insole a portion of the upper exposed by retractive movement of the wipers from over the shoe bottom.
29. A device for pressing upon an insole the marginal portion of an upper wiped inwardly over the insole by end-lasting wipers, said device comprising means for first pressing upon the insole a portion of the upper extending inwardly over the insole beyond the wipers while the wipers are still over the shoe bottom and additional means for thereafter pressing upon the insole a portion of the upper exposed by retractive movement of the wipers from over the shoe bottom, said additional means comprising a plurality of spring-controlled plungers arranged in 50 a series along the margin of the shoe bottom and relatively movable to permit them to assume positions corresponding to the contour of the shoe bottom.
30. A device for pressing upon an insole the marginal portion of an upper wiped inwardly over the insole by end-lasting wipers, said device comprising means for first pressing upon the insole a portion of the upper extending inwardly over the insole beyond the wipers while the wipers are 60 still over the shoe bottom and additional means for thereafter pressing upon the insole a portion of the upper exposed by retractive movement of the wipers from over the shoe bottom, said additional means comprising a plate flexibly conformable to the contour of the shoe bottom and a plurality of springs arranged in a series along the margin of the shoe bottom for pressing said plate upon the upper.
31. A device for pressing upon an insole the marginal portion of an upper wiped inwardly over the insole by end-lasting wipers, said device comprising a member for first pressing upon the insole a portion of the upper extending inwardly over the insole beyond the wipers while 75

the wipers are still over the shoe bottom and another member movable relatively to said first-named member for thereafter pressing upon the insole a portion of the upper exposed by retractive movement of the wipers from over the shoe bottom, and electrical heating means carried by said first-named member for heating both the members.

32. A device for applying pressure and heat to the marginal portion of a shoe upper overlying an insole, said device comprising heated pressing means for engaging and pressing the upper upon the insole first in a location at a distance from the edge of the shoe bottom and additional heated 15 pressing means movable relatively to said first-named means for thereafter engaging and pressing the upper upon the insole in a location nearer the edge of the shoe bottom.

33. A device for applying pressure and heat to the marginal portion of a shoe upper overlying an insole, said device comprising different heated means arranged to press the upper upon the insole respectively in a location at a distance from the edge of the shoe bottom and in a location 25 nearer the edge of the shoe bottom, and a support common to both said means and movable to press the different means successively upon the upper.

34. A device for applying pressure and heat to the marginal portion of a shoe upper overlying an insole, said device comprising different heated 30 means arranged to press the upper upon the insole respectively in a location at a distance from the edge of the shoe bottom and in a location nearer the edge of the shoe bottom, a support common to both said means and movable to 35 press them upon the upper, and springs controlled by said support for pressing upon the upper first the means engaging the upper at a distance from the edge of the shoe bottom and

thereafter the means engaging the upper nearer the edge of the shoe bottom.

35. A device for applying pressure and heat to the marginal portion of a shoe upper overlying an insole, said device comprising a heated plate 5 formed to press the upper upon the insole in a location at a distance from the edge of the shoe bottom, a member movable to press said plate upon the upper, a spring for transmitting the force of said member to the plate, a second heated 10 plate arranged to press the upper upon the insole in a location nearer the edge of the shoe bottom, connections between said member and the second plate for maintaining the latter in spaced relation to the shoe bottom when said first- 15 named plate first engages the upper, and springs for pressing said second plate on the upper by movement of said member.

36. A device for pressing upon an insole the marginal portion of a shoe upper overlying the 20 insole, said device having different relatively movable portions arranged to press the upper respectively in a location at a distance from the edge of the shoe bottom and in a location nearer the edge of the shoe bottom and constructed to 25 apply to the upper in said first-named location greater pressure than in said last-named location.

37. A device for applying pressure and heat to the marginal portion of a shoe upper overlying an insole, said device comprising different 30 members arranged to engage and press the upper respectively in a location at a distance from the edge of the shoe bottom and in a location nearer the edge of the shoe bottom, and means for heating both said members but for heating the mem- 35 ber which engages the upper at a distance from the edge of the shoe bottom to a higher degree than the other member.

WILLIAM PETER LE RETTE.
